(57) **CLAIM**

The ornamental design for an expanded slit-sheet paper cushioning product, as shown and described.

DESCRIPTION

This file of this patent contains at least one drawing/photograph executed in color. Copies of this patent with

color drawing(s)/photograph(s) will be provided by the Office upon request and payment of the necessary fee.

FIG. 1 is a front plan view of the expanded slit-sheet paper cushioning product in an expanded state according to this Embodiment;

FIG. 2 is a right-side front perspective view of the expanded slit-sheet paper cushioning product shown in FIG. 1 taken at an angle to the plane of the paper, such as to look at the expanded slit-sheet paper cushioning product from a right side of the view in FIG. 1;

FIG. 3 is a left-side front perspective view of the expanded slit-sheet paper cushioning product shown in FIG. 1 taken at an angle to the plane of the paper, such as to look at the expanded slit-sheet paper cushioning product from a left side of the view in FIG. 1;

FIG. 4 is a bottom-side front perspective view of the expanded slit-sheet paper cushioning product shown in FIG. 1 taken at an angle to the plane of the paper, such as to look at the expanded slit-sheet paper cushioning product from a bottom side of the view in FIG. 1;

FIG. 5 is a rear plan view of the expanded slit-sheet paper cushioning product shown in FIG. 1 showing an opposite side of the expanded slit-sheet paper cushioning product to that shown in FIG. 1;

FIG. 6 is a left-side rear perspective view of the expanded slit-sheet paper cushioning product of FIG. 1 taken at an angle to the plane of the paper, such as to look at the expanded slit-sheet paper cushioning product from a left side of the view in FIG. 5; and,

FIG. 7 shows a bottom-side rear perspective view of the rear view of the expanded slit-sheet paper cushioning product of FIG. 1 taken at an angle to the plane of the paper and with an inverted line-of-sight, such as to look at the expanded slit sheet paper at an angle from a bottom side of the view in FIG. 6 from an inverted line-of-sight.

The broken lines shown in FIGS. 1-6 depict portions of the expanded slit-sheet paper cushioning product that form no part of the claimed design, and the broken lines shown in FIG. 7 depict both portions of the expanded slit-sheet paper cushioning product that form no part of the claimed design and environmental structure that form no part of the claimed design.
